UNITED STATES PATENT OFFICE.

WILLIAM E. VARNEY, OF DAYTONVILLE, AND WAYNE J. HULL, OF WELLMAN, IOWA.

WOOD-WORKING MACHINE.

SPECIFICATION forming part of Letters Patent No. 279,051, dated June 5, 1883.

Application filed August 26, 1882. (No model.)

To all whom it may concern:

Be it known that we, WILLIAM E. VARNEY and W. J. HULL, citizens of the United States, and residents, respectively, of Daytonville and Wellman, in the county of Washington and State of Iowa, have invented a new and valuable Improvement in Wood - Working Machines; and we do hereby declare that the following is a full, clear, and exact description of the construction and operation of the same, reference being had to the annexed drawings, making a part of this specification, and to the letters and figures of reference marked thereon.

Figure 1 is a side elevation of a machine embodying our improvements. Fig. 2 is an end view, and Figs. 3 and 4 are detail views of parts of the clutch mechanism. Fig. 5 is a cross-sectional view. Fig. 6 is a detail view showing the curved slotted arm and its connections, and Figs. 7, 8, and 9 are detail views showing the mortising-table. Fig. 10 is a vertical cross-sectional view of that portion of the clutch mechanism shown in Figs. 3 and 4.

This invention has relation to wood-working machines; and it consists in the construction and novel arrangement of parts, as will be hereinafter fully described, and particularly pointed out in the claims appended.

In the accompanying drawings, the letter A designates the bench or bed frame to which the adjustable mechanism is attached. The bench-frame is of the ordinary construction, longitudinally slotted and flanged to receive the adjustable parts before mentioned.

The ordinary treadle is employed to operate the mechanism; but steam-power may be applied for this purpose.

A sliding frame is secured to the bench-frame in the usual manner, and having the usual screw-threaded shaft with the center-point for centering the piece to be operated upon, and a screw-clamp for locking the screw-shaft in position, the other end abutting against the ordinary chuck upon the main shaft D, having its bearings in standards rising from the bench-frame, and provided with the usual oil-cups.

E designates an auxiliary or upper mandrel, working in an eccentric sleeve, F, having bearings in the upper ends of arms G G', articulated upon collars H, projecting from the inner faces of the standards I, near their upper ends.

The arm G' is provided at its lower end and below the main mandrel with a curved slotted arm, J, through which a threaded stud, J', extending from the inner standard, I, passes, and is provided with a washer and thumb-nut for securing the upper mandrel in any position to which it may have been adjusted.

The main mandrel D is provided at its outer end with a friction-wheel, K, having a grooved extension, K', for the reception of an endless band, and said friction-wheel K is secured by screws to the inner face of the fly-wheel L. The outer end of the upper mandrel, E, is also provided with a friction-wheel, L', grooved for the reception of the same band, but smaller in diameter than the wheel K. The eccentric sleeve F is provided near one end with an adjusting-lever, M, by which the friction-wheels may be thrown in and out of gear. When the friction-wheels are in gear, the upper mandrel, E, is revolved in a direction away from the operator. A band, M', connects the friction-wheels K and L', and when the said wheels are out of gear causes the upper mandrel to revolve toward the operator. It will be of course understood that both mandrels revolve in the same direction under the same adjustment. The main mandrel D is also provided between its bearings with a double pulley, N, the purpose of which will be hereinafter explained. The outer face of the fly-wheel is provided near its center with a rim or collar, N', projecting in a direction parallel with its periphery. The outer end of the main shaft D, has a countersink to receive a center-point, and this end rests within the bore of the fly-wheel L. A short shaft, N'', pointed at both ends, has one of its bearings within the countersink of the main shaft D, the other bearing being in an arm, O, at the end of the bench or lathe-frame A, an adjusting-screw, O', being employed to compensate for the wear of the short shaft N''. A collar, P, is secured to shaft N'' by a set-screw, and has an inwardly-projecting sleeve provided with a cross-arm, O'', rounded at its ends, as shown. At the end O'' of said cross-arm, and slightly to one side thereof, a screw-pin, P'', is inserted into the inner face of collar P and projects beyond the inner face of the cross-arm O''.

An eccentric ring, Q, provided with projec-

tions $Q'Q''$ in diametrically-opposite positions, has upon the projection Q^2 on its inner face a friction-jaw, R , adapted to embrace the collar, or rim N' when in place. The opposite projection Q' is provided with a friction-block, Q'' , which at times bears upon the outer face of the collar or rim N' . The projection Q' of the eccentric ring Q extends inwardly, as shown, and is provided with a radial slot, R' , through which a screw, R'' , is passed into the collar P , directly opposite the screw-pin P'' , upon which screw R'' the eccentric ring gravitates when rotated, to cause the proper engagement of the friction-clutch. A screw, S , projects inwardly from the inner periphery of the eccentric ring Q at the middle point of the junction of the friction-jaw R , causing the engagement of the screw-pin P'' and the screw S after the friction-jaws have passed the lower end of a vertical central line while the machine is in operation.

Horizontal arms T T' extend laterally in opposite directions from the base of the arm O , the arm T being provided at its outer end with a journal, T'' , upon which is an oscillating band-wheel, T''' , which is connected by a strap to the upper end of the spiral spring T^4 , which is in turn connected at its lower end to an arm, T^5 , projecting from the leg of the bench-frame, as shown. A band or belt, U , is connected by rivets to the periphery of the band-wheel T'' , the other end of said band being connected to the short shaft N'' , so that when the spiral spring T^4 is retracted after having been first extended the band U may be coiled upon the short shaft N'' by the action of the treadle and other operating mechanism hereinafter described. The arm T' is also provided at its outer end with a bearing, T^6 , and in line with the same is a bearing, T^7 , at the end of an arm, T^8 , secured to bench-frame A , between the standards I . The shaft V , having a collar, V' , is journaled in the bearings T^6 and T^7 , its ends projecting beyond said bearings for the reception of an oscillating band-wheel, W , of the same size as the band-wheel T'' , which is, however, set in nearer the fly-wheel a distance equal to the width of its rim. This band-wheel W is also provided with a band, W' , one end of which is riveted to the rim thereof and the other end secured to the short shaft N'' , so as to wind thereon when the band U uncoils therefrom during the operation of the machine. The inner end of the shaft V is provided with a smaller band-wheel, X . To this wheel X is connected a strap, X' , one end of which is secured to the periphery thereof by a rivet, the other end being detachably connected, by a clamp, X'' , or otherwise, to one end of a lever, X''' , the other end of which is permanently secured to the rectangular rock-shaft X^4 , journaled in the rear legs of the bench-frame, near their bases, as shown. A treadle, Y , is also connected to this rock-shaft.

Z designates the adjustable lathe-rest.

As the treadle rises the strap V is unwound

from its collar on the shaft N^2 by the action of the spring T^4 , and at the same time the strap V' is wound upon its collar on said shaft N^2 , and the clutch mechanism is carried backward until a downward movement of the treadle causes it to engage the rim N' and turn the fly-wheel and give it a continuous motion under a repetition of the manipulations of the treadle, the slot R permitting the rim N' to pass while the clutch mechanism is moving backward under an ascending movement of the treadle, while the block Q' engages it and imparts forward motion to the fly-wheel when the treadle is descending. The back gear, Z' , is preferably attached to the standards I I , in order that it may be removed at the same time therewith.

When the disk P , as shown in Fig. 4, is moved contrary to the hands of a clock, the eccentric Q , deriving motion from the pin R^2 , will clamp the rim N' , and the further movement of the pin R^2 will rotate the eccentric and wheel L . When the disk P is moved in the reverse direction—i. e., in the same direction as the hands of a clock—the eccentric Q disengages itself from the rim N' and falls by gravity against pin P^2 , and is carried thereby to its original position.

a designates a table provided with vertical legs a' , passing down through vertical sleeves a^2 at opposite ends of a casting, a^3 , adapted to fit the lathe-frame, and attached thereto adjustably by a bolt and clamping-nut. This table a is provided about the middle of its length with the depending threaded rod a^4 , fixed thereto, which passes down through the sleeve a^5 , rising from the center of the casting a^3 , and provided with a hand-wheel, a^6 , by means of which the table may be adjusted vertically.

The side rails, d d' , of a metallic frame, d^2 , are connected by end rails, d^3 , and are beveled on their inner edges to fit the bevel-edges of the table a . The outer edges of the end rails, d^3 , are beveled downwardly and inwardly to form guides for a sliding bed, e , having depending studs e' e'' on its lower face, against which the curved end of a lever, e^3 , pivoted in a bearing in the side rail d works to operate the sliding bed e forward and backward longitudinally of the lathe to feed material to the cutter and withdraw it after it has been operated upon. The upper face of the bed e is of wood, to protect the cutters. Curved arms f f' rise from the bed e , the curve being toward the cutters, and are connected at their upper ends by a cross-bar, f^2 , near each end, in which work threaded cranks f^3 , provided at their lower ends with a clamping-bar, f^4 , by which the material to be operated upon is held in place on the bed e . The front side rail d' , of the metallic frame d^2 has a threaded depending lug, f^5 , about the middle of its length, for the reception of a screw-bolt, f^6 , by which one end of an adjustable crank-arm, f^7 , is connected thereto. The other end of this crank-arm f^7 is connected by a headed bolt, f^8 , and nuts and

washers to a grooved arm, g , on the upper shaft, g' , of the back gear, Z' , so that this end of the crank-arm may be adjusted by means of the headed bolt f^s within the groove g' of the 5 arm g , to shorten and lengthen the stroke of the crank-arm f^t , which operates the bed e back and forth laterally on the table a . By this means the length of the mortise to be formed by the rotary cutter may be regulated.

10 Power is communicated to the back gear, Z' , by means of a cored spiral wire belt, Z' , leading from the double pulley N upon the main shaft D to a pulley upon the upper shaft, g' , of the back gear, Z' . When the back gear is 15 not used it is only necessary to throw off the wire belt Z^2 .

K' designates the arm for carrying the jigsaw, secured by a bolt, K^2 , to the bench-frame A ; but this forms the subject-matter of a separate application, and is not claimed herein. The free end of the arm K' is provided with vertical ways K^3 , in which a slotted slide, K^4 , works. The lower end of the slotted slide K^4 is provided with a downwardly and inwardly 25 inclined lateral recess, L^t , which is intersected at right angles by a vertical recess, the latter to receive the upper end of the saw-blade.

N^3 is a vertical bearing, in which a rod, N^4 , is vertically adjustable, and is provided at its 30 lower end with an adjustable bifurcated foot, N^5 .

N^2 is a slot in the arm K ; M^3 , a stud in said slot, and M' is a circular saw; but these elements are designed to form the subject of separate applications, and the right is hereby reserved to file the same.

Having described this invention, what we claim, and desire to secure by Letters Patent, is—

40 1. In a wood-working machine, the main shaft D , having bearings in vertical standards removably attached to the bench-frame, and provided near their upper ends with collars projecting from their inner faces, in combination with articulating arms extending upwardly therefrom, one of which is provided 45 at its lower end with a curved slotted arm, and

which are provided at their upper ends with bearings for an eccentric sleeve, in which an auxiliary mandrel works, said eccentric sleeve 50 being provided with an operating-lever, a friction-wheel upon the main shaft secured to a fly-wheel, a friction-wheel upon the auxiliary mandrel adapted to be thrown in and out of gear with the friction-wheel upon the fly-wheel, and an endless band connecting said friction-wheels, substantially as specified.

2. In a wood-working machine, the fly-wheel L , provided on its outer face, near its center, with an annular collar or rim, N' , mounted 60 upon the main shaft D , provided in its outer end with a countersink, in combination with a collar, P , provided with the inwardly-projecting sleeve, having the cross-arm O'' with rounded ends, and the screw-pins P'' and R'' , 65 said collar being mounted upon the short shaft N'' , having center-points on each end which work in countersunk bearings, the eccentric ring Q , having projections $Q' Q''$, the former of which is slotted radially, the projection Q , 70 having friction-jaw R , and the projection Q'' , having friction-block Q''' , and the wheels T^s , X , and W , bands V , W' , and X' , treadle Y , and spring T^t , the same substantially as specified.

75 3. In a wood-working machine, the main shaft D , provided with a double pulley between its bearing-standards, connected by a cored spiral-wire endless band to the pulley of the back gear, having upon its upper shaft 80 a grooved arm, in combination with a crank-arm and a sliding bed provided with securing clamps and a lever for longitudinally adjusting the bed, and a vertically-adjustable table secured to the bench-frame, substantially as 85 specified.

In testimony that we claim the above we have hereunto subscribed our names in the presence of two witnesses.

WILLIAM EDWIN VARNEY.
WAYNE JOSIAH HULL.
